UNITED STATES PATENT OFFICE

2,134,185

GAME APPARATUS

Leslie M. Hansen, Chicago, Ill., assignor to Genco, Inc., Chicago, Ill., a corporation of Illinois

Application January 2, 1936, Serial No. 57,211

4 Claims. (Cl. 273—121)

This invention relates to game apparatuses, and has for its principal object the novel combination and arrangement of parts which will be highly efficient in use and economical in construction.

5 Another object of this invention is to provide a coin operated game apparatus in which it is possible, by the skillful operation of the same, to obtain a free second operation without inserting a coin into the coin slide.

10 Other objects will appear hereinafter.

The invention consists in the novel combination and arrangement of parts to be hereinafter described and claimed.

15 The invention will be best understood by reference to the accompanying drawing showing the preferred form of construction, and in which:

Fig. 1 is a top plan view of a pin and marble game embodying the present invention;

20 Fig. 2 is a longitudinal section taken on line 2—2 in Fig. 1;

Fig. 3 is a bottom plan view of several of the parts embodied in the present invention; and

25 Fig. 4 is a schematic wiring diagram of an electrical circuit embodied in the present invention.

In the drawing, a game apparatus is generally indicated at 10 and is embodied in a cabinet 11 which contains an inclined play board 12 upon which played balls are adapted to be projected by a plunger 15, and formed in the play board 12 are out pockets or score openings 16.

A slide panel 13 is slidably mounted adjacent the lower face of the play board 12 for horizontal movement in a plane parallel to the play board 12.

30 The slide panel 13 when in normal position forms a gate or seat for balls which may be trapped in the pockets 16. There are formed in the slide panel 13 a number of openings 17 corresponding to the number of out openings 16, and these openings 17 are adjacent the pockets 16, that is, out of vertical alignment with but on the same longitudinal axis as the latter.

35 Mounted in the front wall 18 of the cabinet 11 is a conventional coin chute 14 which is engageable with an arm 19 which depends from the slide panel 13 upon which it is mounted.

When a coin of proper denomination and size is placed in the aperture 20 of the coin chute 14, the latter may be moved from left to right (as seen in the drawing) into full stroke position, and in the course of its movement the inner end of the slide 14 will engage the depending arm 19 and cause the slide panel 13 to be moved into ball releasing position; that is, with the openings 17

in vertical alignment with the score pockets of out opening 16.

When balls trapped in the pockets 16 are released by the foregoing movement of the slide panel 13, they drop by gravity onto a ball return runway 21 and gravitate over the latter into a transverse runway 22 which directs the balls to a conventional ball elevating device (not shown). When the coin slide 14 is withdrawn (from right to left, Figs. 1 to 3), the slide panel is returned to its normal position (as shown in the drawing) by resetting springs 28.

Referring more particularly to the invention, there is a pocket or out opening 23 formed in the play board, and disposed below this opening 23 is a ball actuated switch 24 which is mounted upon the slide panel 13. Mounted upon the under side of the play board 12 at its upper end (right end, Figs. 2 and 3) is a solenoid 25 which has an armature 26 that is linked to the slide panel 14 by a yoke 27, for reasons to be presently described.

A switch 30 is mounted in the cabinet 11, as at 29, adjacent the coin chute 14. This switch 30 has a pair of resilient arms which are normally disposed out of engagement with each other. The coin chute 14 has a cam edge 31 on the side which is adjacent the switch 30. This cam 31 is engageable with the switch 30 so as to urge the resilient arms of the switch 30 into engagement with each other.

In conventional coin chutes there is a free motion which is limited by pawls, latches and the like to prevent the inner end of the coin chute 14 from engaging the depending arm 19, but, however, allowing the inner end of the coin chute 14 to be moved from initial position (Fig. 3) to a point adjacent the depending arm 19. In this light it may be seen that by this partial movement the resilient arms of the switch 30 may be brought into engagement with each other for reasons to be explained hereinafter.

A conventional time switch, such as the one disclosed in U. S. Patents Nos. 1,353,850, 1,773,697 and 1,795,969, is embodied in the present invention, and is indicated at 32. This time switch 32 is mounted upon a wall within the cabinet 11 and is actuated by an arm 33 which extends laterally from the coin chute 14.

The present invention embodies an electrical circuit 35 in which is arranged a source of current 34 in the form of a battery of dry cells, the solenoid 25, the ball actuated switch 24, the cam actuated switch 30, and the time switch 32.

During the performance of the game, that is, when the balls are projected onto the play board 55

by the operation of the projector 15, the person operating the projector may by skillful operation of the latter cause a ball to be projected into the pocket 23, whereupon the ball will come to rest 5 on the switch 24 and cause the resilient arms thereof to engage each other, it being understood that when a game is started by the use of a proper coin in the coin chute 14, as has already been explained, that the time switch will be actuated for 10 a predetermined lapse of time so as to allow a complete operation of the game apparatus.

If at the completion of a game (one operation) a ball has been trapped in the pocket 23, the coin chute may be partially inserted, that is, up to a 15 point where it is limited by means of pawls, latches, and the like, so that the cam edge 31 of the coin chute 14 will engage the resilient members of the switch 30 to urge them into engagement with each other; whereupon the circuit 35 20 will be opened and current will flow from the source of energy 34 through the solenoid 25, switches 24, 30 and 32, and back into the source of energy 34.

The foregoing flow of current will cause the 25 coil of the solenoid 25 to attract the armature 26 (left to right), whereupon the slide panel which is linked to the armature 26, as at 27, will be drawn into ball releasing position, that is, with the openings 17 in vertical alignment with the 30 score pockets 16, against the action of the resetting springs 28. All the balls, including the one disposed in the pocket 23, will then drop by gravity onto the ball return runway 21, and will 35 gravitate into the transverse runway 22 which directs them to a conventional elevating device (not shown).

When the switch 24 is moved with the slide panel into ball releasing position and the ball released from the pocket 23, the switch 24 will 40 break the circuit by its own resiliency, and the current in the circuit 35 will cease to flow, whereupon the solenoid will release the armature 26 so that the latter and the slide panel 13 may be returned to normal position by the resetting 45 springs 28.

While I have illustrated and described the preferred form of construction for carrying my invention into effect, this is capable of variation and modification without departing from the 50 spirit of the invention. I, therefore, do not wish to be limited to the precise details of construction set forth, but desire to avail myself of such variations and modifications as come within the scope of the appended claims.

Having thus described my invention, what I 55 claim as new and desire to protect by Letters Patent is:

1. "Free-play" mechanism for use with game apparatus of the type having an apertured ball 60 playing board and an apertured baffle movable back and forth below said board to hold and release balls played into the apertures in the board, a coin-free manually operable control having a limited idle stroke freedom of movement and arranged to move said baffle into ball-releasing position when moved in full stroke operation, spring means normally holding said baffle in ball-retaining position, said "free-play" mechanism including electro-magnetic means for moving said 65 baffle into ball-releasing position, switch means operable by a ball and arranged in circuit with said electro-magnetic means and a manually operable switch positioned for operation by said coin-free control upon idle stroke movement of the same, said ball operated switch being posi-

tioned below said board closely adjacent a ball aperture thereof for operation by a ball played into said aperture substantially as described.

2. "Free-play" mechanism for use with game apparatus of the pin ball type which has a playing board provided with a ball exit opening and a shuffle panel mounted for sliding movement below the board and provided with an exit opening, said shuffle panel being slidable back and forth to move said exit opening into and out of registered relation with the exit opening in said board, said "free-play" mechanism including spring means normally urging said shuffle panel and the exit opening thereof out of registered relation with the exit opening in said board, a solenoid 15 having a plunger operably connected with said shuffle panel, said solenoid being arranged in circuit with switch means mounted on said shuffle panel in a position to be operated by a ball resting in said exit opening of the board, a manually 20 operable control and switch means operable thereby and cooperable with said first-mentioned switch means such that said solenoid may be energized to move said shuffle panel and the exit opening thereof into registered relation as afore- 25 said by operating said manual control when said first-mentioned switch means is operated by a ball as aforesaid, said manually operable control being provided with coin-released detent means and mechanism operatively connecting the control with said shuffle panel for movement of the latter independently of said solenoid when said detent means is released.

3. In a game apparatus of the type including a manual control provided with coin-free detent means normally permitting limited idle stroke movement of the control and operable by deposit of a coin therein to permit full stroke movement of the control, together with a movable resetting means arranged to be moved by said control upon a full stroke operation of the same to release an instrumentality used in playing the game for further play, "free-play" means comprising: electrically operable means for moving said resetting means, a first switch means arranged in said game apparatus to be engaged by said instrumentality, and a second switch means operable by said manual control upon idle stroke movement of the same to close a circuit and energize said electrically operable means for the purpose aforesaid when said first switch means is operated by said instrumentality, whereby said resetting means may be moved independently by said manual control without deposit of a coin therein.

4. In a game apparatus of the type having a ball playing board with ball exits therein and a shuffle panel below said board and normally closing said ball exits to retain balls in the latter, but movable to open the same to release said balls for further play, coin controlled mechanical means for moving the shuffle panel as aforesaid, electrical means for moving said shuffle panel for the purpose aforesaid and arranged in a power circuit including a switch arranged to be actuated by said coin controlled means without necessitating deposit of a coin in the latter, and a second supervisory switch means also arranged in said circuit and positioned in said game apparatus to be engaged and actuated by a ball played into a particular one of said ball exits whereby to permit movement of said shuffle panel by said electrical means for further play without the necessity of depositing a second coin.

LESLIE M. HANSEN.
